UNITED STATES PATENT OFFICE

2,610,027

SPLIT KNOCKER-HEAD JAR AND
SAFETY UNIT

Kenneth E. Waggener, Brea, Calif.

Application August 6, 1949, Serial No. 108,893

4 Claims. (Cl. 255—27)

1

This invention is a combined up-bumping jar and safety joint for deep well tool strings.

Heretofore it has been necessary to unscrew the upper or hammer bowl assembly from a lower or mandrel assembly when the bowl or housing is to be pulled or elevated from a well hole after the hammer has been repeatedly up-jarred on the head or mandrel of the assembly, or following such other operations as a given jar tool may be employed for. Such unscrewing function risks the unscrewing of an assembled string of drill pipe sections at one or more other joints in the string connected to the effective tool at its foot.

Therefore, a purpose of this invention is to provide a simple, practical, substantial, reliable and highly efficient housing and mandrel unit which is readily made up, or as readily disconnected, as to the housing and the mandrel, without risk of unscrewing a jointing screw in an attached tool string. And, in this connection, a purpose is to provide a jarring housing and an anvil mandrel on which latter there is a rigid head which is peripherally interrupted by axially directed gaps so that the head may be regarded as "split" for the free passage upwardly of a complementary hammer which is rigidly combined with the inner face of the housing.

A capacity of the unit is that when the housing is to be pulled from the mandrel it is only necessary to lower the tool string and at the same time exert a left-hand torque whereby to slightly turn the housing and hammer over into register with the passage gaps in the head, whereupon the housing is free to be elevated from the mandrel.

Further, there is provided in the invention a means for closely predetermining a desired hammer impact or "jar" to be delivered to the mandrel, and also jar repeating capacity.

The drawing is a partial axial section of the unit.

Attachable to the lower end of a tool string S (dotted lines) is a top sub 2 screwed at 3 into the upper end of a housing 4 whose lower end has an affixed set of bore-face keys 5 . These keys shift longitudinally along guide ribs $6r$ which are rigid on the lower portion of a substantial mandrel 6 having a joint pin $6p$ for attachment to a subjacent tool or other apparatus not shown.

Such ribs are circumferentially spaced at d to snugly fit the keys 5 when the housing is in its lowest position for positive right-hand or left-hand drive of the mandrel (by operation of its suspending string S during use of the safety joint). In the vertically shifted position of the

housing each key 5 lies snugly between a near face g of a rib and a short laterally, adjacent abutment lug $6a$ of the mandrel so that a right or left hand drive of the mandrel may still be had.

In order to permit the housing to be safely freed from the mandrel the lugs $6a$ (in suitable number) are spaced vertically above a respective shoulder $6e$ to form an escapement passageway W of L-shape and leading out from the top edge of the respective rib $6r$. This enables the escape of the driving keys 5 and safe freeing of the bowl from the mandrel—without unthreading at any joint.

A further feature resides in the provision of a "split" head or anvil flange 7 rigid with the mandrel 6 and spaced longitudinally above the set of ribs $6r$ a sufficient distance to provide for free reciprocation of a set of segments forming a split or circumferentially interrupted hammer 8 rigid with the housing and on its inner face. This permits the longitudinal passage of the hammer as to the mandrel as the housing is lowered or is elevated and works the keys 5 in the respective passageways.

In normal operation the hammer 8 is snapped up against the anvil flange for jarring effect, and by rotating the housing the hammer turns to register with the slots of the mandrel and is then readily elevated with and by the housing when it is to be pulled from the well hole.

It is desired that the jar impact may be delivered with a positive and predetermined force and, also, that the jar may be repeated at will while the tool is in the hole. Means are provided to effect these functions and as here embodied the mandrel has a reduced top stem $6s$ surrounded by a collar 10 having upwardly projecting inwardly pressing spring leaves (or dogs) $10f$. On the tips of the leaves rests a trip ring 11 camming the leaves inwardly under the foot edge $12f$ of a core 12 screwed at 13 onto the mandrel stem $6s$.

The said foot edge $12f$ is bevelled to have an out-thrust camming effect on the engaged tips of the said leaves and in operation will effectively push the ring 11 upward so that the tips of the expanded leaves will slide up along the core 12 .

The leaf collar 10 is normally lodged on a bore bench $4b$ of the housing 4 and is constantly pressed downward by a suitable or preferred spring here being a stack 14 of dished spring rings setting on the ring 11 . The upper end of the spring stack (which surrounds the core 12) reacts on a gland 15 screwed into the lower end

of the top sub 2 which screws into the rim of the housing 4.

The present safety joint-jar unit is lowered or elevated, and/or rotated by the tool string S to which the sub 2 may be attached.

It will be observed that when the sub 2 is screwed into the housing the gland 15 will engage and compress the spring stack 14 onto the ring 11 and this will contract the tips of the controlling leaves 10f and hold them under the tripping wedge cam 12f, while the collar 10 is butted on the bench 4b. Therefore, when there is set up a certain tension in the tool string and the attached housing 4 the tripping cam 12f will push the tips of the dogging leaves outward freeing the collar upward just as the load of the preset spring stack is overcome. The released collar will ride up along the core 12 and concurrently the housing hammer will be snapped up to the anvil flange by effort of the tensioned tool string S; this operation taking place as the housing keys slide along their guide ribs. Repeat jar is had by merely lowering the housing to again set the dogging leaves under the core cam 12f.

Rotating torque can be put on the mandrel when the keys are in their upper or lower positions as to the guiding ribs.

When the housing is to be elevated and pulled from the mandrel, as is sometimes desired, left-drive torque on the string will turn the keys into the escape passageways of the ribs and then housing elevation will entirely clear the split hammer and the therewith aligned keys out of the said windows.

What is claimed is:

1. A combined up-stroke jar and safety joint unit comprising a mandrel having a peripheral flange circumferentially split to form longitudinal slots from top to bottom and constituting an anvil, and a housing rotative on the mandrel and having an internal hammer flange split complementally to the said anvil flange to be passed along each other for attachment or detachment and facilitate assembly or disassembly of the housing and the mandrel, and including bore face keys fixed on the housing and in alignment with and below parts of the hammer flange, and ribs fixed on the mandrel and forming guides for the longitudinal shift of the housing keys and the hammer flange toward or from the mandrel flange; the ribs having guide passageways for withdrawal of the keys by and with the housing and said hammer flange between said mandrel slots; the anvil striking hammer flange parts being wider than the said aligned keys to give 45 long wear life.

2. In a safety joint assembly for deep well-hole tools, a mandrel having an external anvil flange which is interrupted circumferentially by longitudinal slots and having circumferentially spaced guide ribs below and aligned with parts of said flange and form escapement passageways aligned with said flange slots, an elongate housing enclosing the mandrel and having keys fixed on its bore face and movable along the mandrel 10 and turnable into said passageways, and an annularly interrupted hammer flange rigidly fixed on the inner face of the housing located above and in alignment with and which hammer flange includes jarring portions less in width than the width of said slots and being movable through said slots when the keys are aligned therewith; parts of the spaces between the ribs being longitudinally aligned below the slots in the interrupted anvil flanges.
3. A well tool safety joint assembly including a housing whose lower end is provided with internal, affixed, circumferentially spaced hammer segments and with affixed keys aligned with and below said segments, and a cylindrical mandrel 25 member slidably mounted within said housing and provided with affixed, external circumferential anvil segments whose lower faces are engageable with and by said hammer segments, the circumferential spaces between the anvil segments being greater in width than the width of the hammer segments so that the housing may be lowered onto or pulled from the mandrel, and guide members on the mandrel mounted below said anvil segments and cooperating with the said 30 keys to lead the hammer segments to the anvil segments for jar effect or for escape from the mandrel.
4. The assembly of claim 3; and spring latch means mounted in the housing and engaging and yieldably locking the mandrel in the housing in open position of the hammer segments from the anvil segments.
